UNITED STATES PATENT OFFICE.

HOLLON C. SPAULDING, OF BOSTON, MASSACHUSETTS.

TELEGRAPHIC PRINTING APPARATUS.

SPECIFICATION forming part of Letters Patent No. 559,821, dated May 12, 1896.

Application filed April 23, 1895. Serial No. 546,935. (No model.)

To all whom it may concern:

Be it known that I, HOLLON C. SPAULDING, a citizen of the United States, residing at Boston, in the county of Suffolk and State 5 of Massachusetts, have invented a certain new and useful Improvement in Telegraphic Printing Apparatus, of which the following is a specification.

The object of my invention is to provide a 10 printing apparatus susceptible of being readily operated by electricity without the employment of a skilled telegraph-manipulator, and adapted especially for large-scale printing, such as bulletins. Obviously any contrivance for printing on any scale messages 15 or announcements which may be used by persons accustomed only to the ordinary reading-text must be capable of printing any letter of the alphabet and any numeral, punctuation-mark, or other common symbol; and it 20 is equally obvious that for printing on a large scale by an apparatus capable of fulfilling this requirement any contrivance which requires a separate type, die, or other impression-maker for each desired character will be 25 undesirable, bulky, and extremely costly.

For telegraphic bulletin-printing, to which my invention is especially adapted, where the letters, to be legible at a distance, should be 30 from three to five inches high and correspondingly wide, any apparatus must necessarily be of large size; but an apparatus employing individual type-pieces would be of such size as to make its use in most places impracticable. 35 The following description, read in connection with the drawings hereto annexed, in which like letters and figures are used always to designate like parts, will enable any one skilled in the art to which my invention pertains to practice it.

Of the drawings, Figure 1 is a conventional chart showing the principle of operation of the elementary printing contrivance. Fig. 2 shows the same arrangement as Fig. 1, with 45 suggestions as to details of arrangement. Fig. 3 represents a form of printing element with mechanical connections. Figs. 4 and 5 show in front and side view, respectively, a form of carriage to contain and convey a printing 50 contrivance constructed according to the plan outlined in Figs. 1 and 2. Figs. 6 and 7 show in plan and partial section a set of contact-

strips which connect at the sending-station with appropriate wires of the cable which passes to the printing apparatus. Figs. 8 and 55 9 show the under side and a cross-section of a sending-key, while Figs. 10 and 11 show the manner of mounting the sending-keys on the table of contact-strips shown in Figs. 6 and 7. Fig. 12 represents a complete bulletin-printing apparatus in a suitable case with the front 60 removed, and Fig. 13 is a view from the left side of the apparatus of Fig. 12 in section along the broken line *z z*. Figs. 14 and 15 show details of the line-spacing mechanism, 65 and Figs. 16 and 17 details of letter-spacing mechanism.

My printing contrivance consists of an assemblage of printing elements grouped, by preference, in a rectangle and arranged in 70 abscissa and ordinate lines. Each of these printing elements is susceptible of independent movement, and any selected groups of such elements may be moved simultaneously.

The arrangement of impression elements 75 which I find to be the best for all practical purposes is shown in Fig. 1. This figure is for the most part conventional; but the absence therefrom of construction details serves to simplify the description. Details are developed in other figures of the drawings.

In Fig. 1 is indicated the assemblage of printing elements arranged in a rectangle, five-square, with intermediate elements in the second and third horizontal lines. Two 85 detached circles distinguished by a cross-mark within their circumferences are auxiliary members of the assemblage, whose functions will be described presently. Assume for the present that each circle of the assemblage represents a printing element capable of making a circular dot upon a receiving-surface and that each element is actuated by an electromagnet. I connect each electromagnet with one of five circuit branches 95 which correspond to the five vertical lines and with one of seven circuit branches which correspond to the horizontal lines, the rows of elements intermediate between the vertical rows being relegated to circuit branches of 100 their own, thus making the circuit branches for the horizontal rows of elements seven in number. The designations applied in Fig. 1 to the impression elements indicate the dis-

tribution of circuit connections. Thus there are five circuit branches, which contain the five vertical rows of elements, these branches being numbered 1 2 3 4 5, respectively, and 5 seven circuit branches for the horizontal rows of elements lettered A B C D E F G, respectively. Each impression element is designated by a figure and a letter, according to the position of the element in the circuit branches. All elements marked 1 are in circuit branch 1, and all marked 2 in circuit branch 2, and so on, while all elements marked a are in circuit branch A, all marked b in circuit branch B, and so on. In one set of circuit branches are interposed sources of electrical energy, one for each branch of the set. These are shown in Fig. 1 conventionally as interposed in the numeral-marked branches 1 2 3 4 5.

20 In order to actuate the printing elements, or sets of them, I bring the two sets of circuit branches into juxtaposition, but not into closure contact, as shown at Y. The five numeral-marked branches cross the seven letter-marked branches, so that contact may be made at any of the thirty-five (5×7) intersections of these branches. If where branch 2 crosses over branch D contact is made, a current passes through element 2^d in the assemblage X and energizes the electromechanical contrivance to print a spot or make a perforation, according to the nature of the device which the impression element is assumed to represent. Likewise, if any number of the 35 circuit-intersections at Y be made the loci of contacts, the corresponding impression elements at X will be actuated and the aggregate of all the spots or punctures so made will constitute the outline of a legible character. Thus to make letter "M," which is outlined by the cross-hatched impression elements at X in Fig. 1, we must actuate 1^a and 5^a, 2^b and 5^b, 1^c and 5^c, 1^d, 2^d, 4^d, and 5^d, 1^e and 5^e, 3^f and 4^f, 1^g, 3^g, and 5^g. To accomplish this, 40 make contacts at Y, as indicated by the dotted circles—namely, where branch 1 crosses branch A, where branch 5 crosses branch A, where branch 2 crosses branch B, where branch 5 crosses branch B, where branch 1 crosses branch C, where branch 5 crosses branch C, where branch 1 crosses branch D, where branch 2 crosses branch D, where branch 4 crosses branch D, where branch 5 crosses branch D, where branch 1 crosses branch E, where branch 5 crosses branch E, where branch 3 crosses branch F, where branch 4 crosses branch F, where branch 1 crosses branch G, where branch 3 crosses branch G, where branch 5 crosses branch G—55 and by the aggregate impression made by the seventeen impression elements at X the letter "M" will be formed upon whatever suitable surface is presented to the face of the assemblage X. By this means I can use a set of 60 wires equal to the sum of the vertical and horizontal lines of my assemblage, and at the same time select any number of elements up

to that equaled by the product of the vertical and horizontal lines. Thus with five vertical-row circuit branches and seven horizontal-row branches, requiring twelve wires, I can control five times seven elements at the printing-station.

I have shown elements 1^b and 1^c at one side of the printing assemblage. These elements 75 may represent electromechanical contrivances for feeding the surface to be printed on by the printing assemblage or for moving a carriage which contains the printing mechanism. 1^b and 1^c are available for any purpose auxiliary to the printing. By using this contrivance in the manner specified it is true that a great number of shunted currents spread through the conductors of the assemblage X; but the line of least resistance is 85 always taken through the element whose connections are common to the contact made at Y, and that element is thus the one actively energized. By the artifice described any letter of the alphabet or any numeral and all 90 necessary symbols and punctuation-marks may be made by selecting from the assemblage X an appropriate group of elements through the contact area Y and energizing them simultaneously. Automatic closure-selectors may be employed, so that any one capable of operating a type-writer may operate this printing contrivance. If the circuit branches are subdivided so as to form as many 100 contact areas as there are desired characters, an automatic circuit-selecting key may be provided for each contact area and the successive characters printed without requiring more than the selection of an appropriately-marked key. By securing relative movement 105 between the printing assemblage X and the surface on which the group-impressions are made, as by the operation of a feed by means of element 1^b, the successive impressions may be made to form connected words and sentences. The automatic closure keys or selectors and the manner of applying the contrivance described to a detailed mechanism will presently be described.

Figs. 2 and 3 show a method of applying 115 electromechanical devices to the elements of the printing assemblage X shown in Fig. 1. In Fig. 2 again I show the assemblage X, but this time with each of its elements connected (conventionally) to an electromagnet. 120 Each electromagnet is marked as was the printing element to which it is connected where the printing elements were shown conventionally in Fig. 1. Thus magnet 1^a is mechanically connected with the printing 125 element marked 1^a in Fig. 1, the marks in Fig. 1 designating, as was explained, the printing element and all the energizing apparatus connected with it.

In Fig. 3 is shown a form of printing element and a manner of connecting it with an electromagnet. Magnets M M', which may represent any of the magnets of Fig. 2, have 130 armatures N N', to which are attached links

L L', in turn attached to bell-crank levers H H', which, through suitable connecting-rods, are articulated to the printing-plungers P P'. A surface 29 (shown in Fig. 3 in cross-section) 5 stands in such relation to P and P' that when magnets M M', or either of them, are energized the pad ends of P or P' are pressed against the surface 29. The pads may be spongy lumps kept wet with ink or may operate on an inking-ribbon placed between them and surface 29.

Returning to Fig. 2, assume that each of the conventional connections between the magnets at 1^a 2^a, &c., represents such a contrivance as that shown in Fig. 3 and that each of the elements of X represents a printing or inking plunger. If then the circuit branches be conventionally represented in Fig. 2 by the line groups 1 2 3 4 5 and A B C D E F G, 15 respectively, the connections with these circuit branches are made as indicated. Magnet 1^a is connected at one end of its coil with branch 1, and at the other end of the coil with branch A, magnet 2^a with branches 2 and A, 20 and so on. Magnets 1^a, 2^a, 3^a, 4^a, 5^a, 2^b, 3^b, 4^b, 5^b, 1^c, 2^c, 3^c, 4^c, and 5^c are shown connected with circuit branches A B C and 25 1 2 3 4 5. The same principle of arrangement for the remaining magnets is contemplated, but is not shown. To energize a selected group of printing-element magnets, selective contacts are made at the contact area Y, as shown in Fig. 2, in the manner described in connection with Fig. 1.

35 By Figs. 4 and 5 I show means of applying my printing device to a movable carriage. A box K is hung on two rails by wheels w w, so that it may be drawn across the face of the sheet or roll on which the printing is to be made. In these two figures the sheet and the feed mechanism are not shown, description of those details being reserved for further figures. In the box K are mounted the printing-members P P', and an assemblage of printing-magnets, such as shown in Fig. 2, is mounted within the box. Behind the box K, and running parallel with the traverse of the box upon its wheels, are two groups of metallic strips. These strips constitute the circuit 40 branches which were shown conventionally in Figs. 1 and 2, and are designated in correspondence with the symbols already adopted, the upper set of strips being marked 1 2 3 4 5, the lower set A B C D E F G. In the back 45 of the box are fastened a number of spring-trailers s, which bear on the circuit-strips. These trailers are electrical conductors insulated from each other in their attachment to the box K. Adopting the arrangement indicated in Figs. 1 and 2, there are five spring-trailers in contact with strip 1—namely, trailers corresponding to contacts with circuit branches A, C, D, E, and G. Upon each of the strips 2 3 4 5 rest seven trailers, corresponding 50 to contacts with circuit branches A B C D E F G. Upon each of strips A, C, D, E, and G five trailers make contact corresponding to

circuit branches 1 2 3 4 5. On strips B and F only four trailers make contact—namely, those corresponding to circuit branches 2, 3, 4, 70 5 and 5. The coils of magnets 1^a, 1^c, 1^d, 1^e, and 1^g are connected each with one of the trailers on strip 1. The coils of magnets 2^a, 2^b, 2^c, 2^d, 2^e, and 2^g are connected each with one of the trailers on strip 2. The coils of 75 magnets 3^a, 3^b, 3^c, 3^d, 3^e, 3^f, and 3^g are connected each with one of the trailers on strip 3. The connections of the remaining magnet-coils with the strips 4 and 5 are made in the same way. Then the coils of magnets 80 1^a, 2^a, 3^a, 4^a, and 5^a are connected each with one of the trailers on strip A. The coils of magnets 2^b, 3^b, 4^b, and 5^b are connected each with one of the trailers on strip B, and so on. Thus through the trailers each impression-element actuator is connected with one of the strips of the numeral group 1 2 3 4 5 and with one of the strips of the letter group A B C D E F G. If to each numeral-strip and letter-strip is connected a line-wire and these 85 wires are grouped as in group Y of Fig. 1, selection of contacts at the intersection of these line-wires will determine the printing-magnets to be energized at the box K, and with the arrangement of printing-elements X, Figs. 90 1, 2, and 4, contacts made simultaneously at a selected group of intersections at Y will result in the printing of a legible character in dotted lines upon whatever surface is presented to the printing contrivance carried by 95 the box K of Figs. 4 and 5.

Figs. 6, 7, 8, 9, 10, and 11 illustrate a form of transmitting-key board to be used at the end of the cable remote from the printing-frame of Figs. 4 and 5.

105 The wires A^X B^X C^X D^X E^X F^X G^X, leading from contact-strips A B C D E F G, Figs. 4 and 5, branch from the cable and connect with strips A' B' C' D' E' F' G, respectively, these last-named conducting-strips being secured 110 to a table y, but insulated therefrom, Figs. 6 and 11. Upon the strips of table y are secured spring-pairs 8, Fig. 7. From the cable x the wires which connect with contact-strips 1 2 3 4 5, Figs. 4 and 5, pass to keys O, Figs. 115 8, 9, 10, and 11. In keys O are conducting-strips 1⁰ 2⁰ 3⁰ 4⁰ 5⁰, to which wires 1^X 2^X 3^X 4^X 5^X are connected, respectively. From key to key the circuit branches are continuous. To strips 1⁰, &c., are attached springs, as 7, 120 Figs. 8, 9, and 11, and at the corners of the keys O posts p are secured, which pass through holes h in table y. Springs l on posts p keep keys O normally elevated, and stops m on the ends of posts p prevent the springs 125 l from throwing key O out of its seat.

In Fig. 10 is shown the arrangement of two keys O O with relation to the circuit branches. From the cable-wires branches are led to sets of table-strips A' B' C' D' E' F' G' and A² B² 130 C² D² E² F² G², the wires to A' and A² being branches of the same line-wire, and so on. From the cable the wires leading from the contact-strips 1 2 3 4 5 are also branched to

feed as many wires of keys O as are desired. Between one key O and the next flexible connections are made by having coils of slack wire, as shown in Figs. 8 and 10. By means of springs such as 7 and 8, Figs. 9 and 7, placed over each other—springs 7 in the key O and springs 8 on strips in table y—contact may be made and circuits closed by selecting intersections of circuit branches after the manner of Y in Fig. 1. Each key O carries a determined number of springs 7, attached to the metallic strips on the under side of the key, and a corresponding number of springs 8 project up from the table-strips. The converging pairs of springs 7 enter the forking pens of springs 8 and make sure contact. The A B C D E F G circuit branches are thus connected with the 1 2 3 4 5 circuit branches and the printing-element controllers at the receiving end of the cable are energized according to the selection of circuit-branch intersections.

Figs. 12 and 13 exhibit an assembled apparatus for printing by means of the invention described above. A case 21 is provided with a glass front 22 and contains rollers 23, 24, and 25. On the roll 23 is wound a band of paper which travels back of the glass front of case 21. The feed-rolls 24 and 25 operate to move the paper sheet a uniform distance for line-spacing. Behind the paper and traveling on rails 26 and 27 on the back of the case 21 is the printing-box K, arranged as shown in Figs. 4 and 5. The contact-strips 1 2 3 4 5 and A B C D E F G are secured to but insulated from the back of the case, and from the pinching-screws 28 at the ends of the said contact-strips run the wires which pass to the cable (not shown) which communicates with the keyboard in the sending-station, described in connection with Figs. 6 to 11. The printing-plungers P, arranged as in Figs. 3 and 4, present their acting ends to the paper strip 29 just below the lower edge of the glass case-front. An inking-pad 30 on the other side of the paper extends along the front of the case, so that the pressure of plungers P on the back of the paper produces corresponding spots on the front. The box K has a traverse entirely across the box, and this traverse-feed for letter-spacing I accomplish as follows: Reverting to Fig. 1, I provide two extra elements, which are there marked 1^b and 1^f. Contacts for energizing these elements are made exactly as for those within the printing-square; but instead of using these two 1^b and 1^f for printing I avail myself of them to secure the feed movements necessary to bulletin-printing in successive lines. Thus in Figs. 12 and 13 I show the carriage K as moved by cords 31 and 32, one of which, 31, passes to a pawl-moved drum 33 and the other to a weight 34. The winding-up drum is operated by a magnet 35 and its armature 36, in connection with a spring 44. This magnet is thrown into circuit by the contact which energizes the element 1^b, and is, in short, the electromechan-

ism represented conventionally by 1^b in Fig. 1. I prefer to have the magnet 35 in a local circuit which will be closed by the action of the 70 line-magnet energized by contact for 1^b.

The operation of the letter-space feed is shown in Figs. 16 and 17.

A compound pulley 39 is constructed with an outer wheel or drum 33 and inner wheel 41. On the projecting flange of the inner wheel 38 is a groove 42, in which the cord 37 is wound and fastened. The inner wheel 41 is provided with a friction-clutch 43, which binds it to the outer wheel 33 when cord 37 is pulled. The other end of cord 37 is fast to the end of a lever 36, which is normally held back by a spring 44, Fig. 12. When magnet 35 is energized, its pull on the armature 45, fastened to lever 36, overcomes spring 44, and 85 the cord 37 is slackened. A light torsion-spring 46, which always tends to turn the inner wheel 41 on the stationary shaft 47, winds the cord 37 in the groove 42. Then when the magnet 35 is demagnetized spring 44 reasserts 90 itself and brings lever 36 back against the stop 9, the inner wheel is turned by the pull of the cord 37, the inner wheel grips the outer wheel 33 by means of the clutch 43, and the cord 31, which goes to the carriage K, Fig. 12, 95 is wound on the outer wheel or drum 33, drawing the carriage K ahead one letter-space. A pawl 48 and ratchet 49 on the flange of drum 33 detain the drum 33, normally permitting only the winding-up motion.

By having the circuit which controls magnet 35—namely, 1^b and its corresponding circuit branches—closed by the action of every letter-key of the keyboard shown in Figs. 6 to 11 while each letter-impression is being 105 made at P on carriage K the letter-space-feed mechanism gets into position to feed the carriage K along its traverse-rails 26 and 27. When the letter-key is released, the contact 1^b is broken, magnet 35 is demagnetized, and 110 the spring 44 pulls the carriage along one letter-space. For spacing alone one key having only contact 1^b is easily provided. The return traverse of carriage K is accomplished by releasing the pawl 48 from the ratchet 49 115 of wheel 33. The weight 34 then pulls the carriage K back to the beginning of a line. The magnet 50, which lifts pawl 48, is in the same circuit with the line-space electromechanism, so that when the roll of paper is moved 120 up one line-space the printing-carriage is automatically returned to the beginning of a line. The line-spacing is accomplished through the selected contact of 1^f of Fig. 1.

An electromagnet 51, Figs. 12, 14, and 15, 125 is in the circuit selected by contact 1^f and operates on an armature-lever 52, which, rising, lifts the catch 53 by the trigger 54. The catch 53 holds a drum 55 from rotating under the pull of weight 56 on the cord 57, wound on the drum, by means of the two-tooth ratchet-wheel 58, which is fast to the drum 55. A ratchet-collar 59 holds the drum in engagement with rolls 24 and 25, which grip the

paper sheet by means of spikes 60 on roll 25, which mesh with corresponding holes in roll 24. The ratchet-collar 59 permits the cord 57 to be wound on the drum 55. When contact 5 1¹ is selected, the magnet 51 picks up armature-lever 52 and catch 53; but the trigger 54 on catch 53 is tripped by engagement with a stop 61, and the catch 53 falls immediately after being lifted and cannot be lifted again 10 until armature 52 has been released and drops below the trigger 54. Thus the drum can revolve only until the next tooth of the ratchet-wheel 58 engages the catch 53. The distance which the drum can revolve determines the 15 space through which the paper sheet is fed upward.

Magnet 50 of Figs. 12, 16, and 17, which controls the releasing-pawl for the back traverse of carriage K, is, as has been said, in 20 circuit with magnet 51, so that when the paper is moved up a line-space the printing-carriage moves back by the pull of weight 34 on cord 32 to begin another line. The paper after it passes to the top of case 21 can be led 25 out at the back and disposed of as desired. It is shown in Figs. 3, 12, and 13 as wound on a lower roll 62 in the case 21.

The mode of operation of my invention is obvious from the description of details already 30 entered into. Having a multiple keyboard arranged according to the plan indicated in Figs. 6, 7, 8, 9, 10, and 11, all that devolves on the operator at the sending-station is to depress the keys in succession with deliberation measured by the size of the printing apparatus and the inertia of its moving parts. The printing assemblage on the carriage K will thus operate to print desired characters 35 by selected groups of plungers, and the traverse letter-feed will go on automatically. The line-feed and return traverse-feed complete the movements necessary to continuous printing on the bulletin-roll.

I claim as my invention—

45 1. An assemblage of impression-making elements distributed in two dimensions, each element having its proper actuator, the assemblage containing such a number of impression elements and in such disposition that by 50 the operation of selected groups of impression elements there may be formed, within the bounds of the assemblage the outline of any one of a plurality of characters, in combination with means whereby any desired 55 character group of elements may be selected and simultaneously actuated to form a character, and a surface in juxtaposition to the said assemblage of impression elements susceptible of receiving the impression from an 60 actuated group of impression elements.

2. An assemblage of impression-making elements distributed in two dimensions arranged in ordinate lines and abscissa lines, each element having its proper actuator, the 65 assemblage containing such a number of impression elements, so disposed in the said ordinate and abscissa lines that by the opera-

tion of selected groups of impression elements there may be formed the outline of any one of a plurality of characters, in combination 70 with means whereby any desired character group of elements may be selected and actuated to form a character, and a surface in juxtaposition to the said assemblage of impression elements susceptible of receiving the impression from any selected group of impression elements. 75

3. An assemblage of impression-making elements distributed in two dimensions, each element having an electrical actuator, the assemblage containing such a number of impression elements and in such disposition that by the operation of selected groups of impression elements there may be formed within the bounds of the assemblage the outline of 85 any one of a plurality of characters, in combination with selective contact-makers, whereby any desired character group of elements may be simultaneously operated, each by its electrical actuator, to form a character, and 90 a surface, in juxtaposition to the said assemblage of impression elements susceptible of receiving the impression from an actuated group of impression elements.

4. An assemblage of impression-making 95 elements arranged in ordinate lines and abscissa lines, each element having an electrical actuator, the assemblage containing such a number of impression elements, so disposed in the said ordinate and abscissa lines that 100 by the actuation of selected groups of impression elements there may be formed within the bounds of the assemblage the outline of any one of a plurality of characters, in combination with selective circuit contact-makers, whereby the circuits of any desired group 105 of electrical actuators for a group of impression elements may be closed, and the impression elements thus selected may be actuated to form collectively a character, and a surface, 110 in juxtaposition to the said assemblage of impression elements susceptible of receiving the impression from any selected group of actuated impression elements.

5. An assemblage of similarly-shaped impression-making elements, each element having its proper actuator, the assemblage containing such a number of similarly-shaped impression elements and in such disposition that by the operation of selected groups of such impression elements there may be formed within the bounds of the assemblage the outline of any one of a plurality of characters, in combination with means whereby any desired character group of elements may be selected 125 and simultaneously actuated to form a character, and a surface in juxtaposition to the said assemblage of impression elements susceptible of receiving the impression from an 130 actuated group of impression elements.

6. An assemblage of similarly-shaped impression-making elements distributed in two dimensions, each element having an electrical actuator, the assemblage containing such a

number of impression elements and in such disposition that by the operation of selected groups of such impression elements there may be formed within the bounds of the assemblage 5 the outline of any one of a plurality of characters, in combination with selective contact-makers whereby any desired character group of similar elements may be simultaneously operated, each by its electrical actuator, to 10 form a character, and a surface, in juxtaposition to the said assemblage of impression elements susceptible of receiving the impression from an actuated group of elements.

7. The combination with an assemblage of 15 impression-making elements, containing such a number of impression elements and in such disposition that by the simultaneous operation of groups of impression elements selected out of the assemblage there may be found 20 the outline of any one of a plurality of characters, of a carriage for said assemblage of impression elements, and a surface in juxtaposition to said assemblage susceptible of receiving the impression from any selected 25 group of impression elements, said carriage and surface being movable relatively to one another.

8. The combination with an assemblage of impression-making elements, each element 30 having its proper electrical actuator, the assemblage containing such a number of impression elements and in such disposition that by simultaneous operation of selected groups of impression elements there may be formed 35 the outline of any one of a plurality of characters, of a carriage for the said assemblage and its actuators, and a surface in juxtaposition with the said assemblage susceptible of receiving the impression made by a group 40 of impression elements; said carriage and said surface being movable relatively to each other.

9. A circuit-selecting device consisting of sets of circuit branches, one set superposed

upon the other so as to bring the branches of one set across the branches of the other, in combination with a key having a plurality of contact-controllers corresponding in location with determined intersections of the circuit branches, so arranged that by the operation of the key electrical connection between the branches of the sets may be controlled and determined at any group of intersections of circuit branches.

10. A circuit-selecting device consisting of 55 sets of circuit branches normally open, one set superposed upon the other so as to bring the branches of one set across the branches of the other, in combination with a key having a plurality of contact-closers corresponding in location with determined intersections of the circuit branches, so arranged that by the operation of the key electrical connection between the branches of the sets may be established at any group of intersections of circuit branches.

11. A circuit-selecting device consisting of sets of circuit branches normally open, one set terminating in contact-strips in a keyboard, the other set terminating in contact-strips in a key, the key presented to the keyboard in such manner that the branches of the two sets lie in intersecting lines, the said key and board being normally apart, in combination with contact-points between key and board in connection with the terminal strips of one or the other branches and means for bringing the said contact-points into touch with the strips of the opposite set whereby circuit-closures at a group of intersections of the circuit branches are effected.

In testimony whereof I have signed my name to this specification in the presence of two subscribing witnesses.

HOLLON C. SPAULDING.
